UNITED STATES PATENT OFFICE.

MARTIN A. HAYWARD, OF ELMWOOD, MASSACHUSETTS.

HANDLING-HORSE FOR SHOE-UPPERS.

1,359,370.

specification of Letters Patent. Patented Nov. 16, 1920.

Application filed February 28, 1920. Serial No. 362,160.

To all whom it may concern:

Be it known that I, MARTIN A. HAYWARD, a citizen of the United States, residing at Elmwood, in the county of Plymouth, State of Massachusetts, have invented a certain new and useful Improvement in Handling-Horses for Shoe-Uppers, of which the following is a specification, reference being had therein to the accompanying drawings.

10 This invention has relation to appliances employed in boot and shoe making, and in particular to the so-called handling- or carrying-horses which are employed in shoe factories for receiving, holding, transporting, or storing, in pairs, the uppers for a lot or case of shoes.

15 A so-called handling-horse or carrying-horse comprises, in brief, a pair of parallel arms upon which the uppers are placed, sometimes with the rights upon one arm, the lefts upon the other, as fast as any given operation upon the uppers may be performed. The complete lot or case of uppers having been received upon the arms of the horse, the free extremities of said arms are shackled together so as to prevent escape of uppers from the arms, and the loaded and closed horse is transported to the required point, the uppers remaining stacked thereon until removed by a workman for the performance of the next operation in connection therewith.

In practice heretofore, in order to retain upon the upper-carrying arms the uppers which have been placed upon them, the ends of the said arms have been connected together in different modes. Different forms of shackles or retainers have been employed, and various locking devices and expedients 20 in connection with such shackles or retainers, have been devised also. Such modes and contrivances have been found deficient in certain respects, and consequently have not proved entirely satisfactory. One material deficiency has been a liability to unshackling or releasing of the extremities of the arms, permitting escape or loss of uppers from the latter. In the case of certain of the 25 said shackles or retainers the grasp of the hand of a person in picking up or carrying the loaded horse, quite naturally encircling both arms at a point above the topmost of the uppers thereon, and tending to press the extremities of the arms inward toward each 30 other, very frequently releases the arms from

the engaging device when such result is not intended. The locking devices which have been contrived and applied for prevention of accidental unshackling and the consequent escape or loss of uppers, have proved 35 faulty and unreliable, and have been useful only to a limited extent. In some instances, they have been of such a character as to become automatically unlocked through the horse being turned upside down. In others, 40 they have been so constructed and applied that the workman has been liable to take hold of, or otherwise move, the locking device in lifting the loaded horse, and thereby 45 unlock the arms unintentionally.

50 The general object of the present invention is to remedy the deficiencies of devices heretofore employed for shackling together the extremities of the arms of a handling-horse, and for locking such arms in shackled condition. More particularly, an object is 55 to provide in connection with the arms and their shackle or retainer a locking contrivance of such a nature that accidental or unintentional unlocking and release of the 60 arms is practically impossible.

The invention consists in the combination in a handling-horse having its opposite arms formed with reduced portions adjacent the free ends thereof, and a shackle or retainer 65 having holes through which the extremities of said arms may be passed, and having also slots which lead away from said holes and into which the reduced portions of the arms may enter by transverse movement from 70 said holes, of a stem between said holes, and a locking member movable along said stem and adapted to engage with said arms 75 to lock them in the slots, said stem having a stop for said locking member so located 80 that it prevents the latter from separating bodily from the shackle or retainer to an extent equal to the extent of projection of the end-portions of the arms beyond the shackle or retainer. The said locking member, 85 thus limited in the extent of its separation bodily from the shackle or retainer, is adapted to be tilted relative to the stem, to permit the arms to be pressed alternately along the slots into the holes to permit their 90 withdrawal from the shackle or retainer.

95 The preferred embodiment of my device is shown in the accompanying drawings, in which—

100 Figure 1 is a perspective view of a load.

ing horse mounted in upright position upon a support therefor, it being shown as having locking means according to the present invention combined with its arms and its 5 shackle or retainer.

Fig. 2 is a plan view of the parts at the upper end of the horse, showing the manner in which the locking means prevents the arms from being moved inward into the 10 holes in the shackle or retainer.

Fig. 3 is a side elevation of the parts which are shown in Fig. 2, in the same relations as in Fig. 2.

Fig. 4 is an end elevation of same.

15 Fig. 5 is a side elevation showing one step of the procedure in disengaging the shackle or retainer from the arms.

Fig. 6 is a plan view of the shackle or retainer, with its hook, stem, and locking device removed.

Fig. 7 is a detail view in section on line 7-7 of Fig. 2, on a larger scale than the preceding figures.

The horse shown in Fig. 1 is made of a 25 length of heavy spring wire bent upon itself into elongated U-form, it comprising the two long, substantially parallel, arms 1, 1, at the lower ends of which horizontal foot portions 1^b, 1^b, extend toward each other 30 and are united in a stem 1^c which is made by twisting upon itself the middle portion of the said length of wire. The said stem, as indicated in Fig. 1, is designed to be entered into a socket 1^d in a floor 1^e, or 35 bench or other support, to hold the horse in upright position adjacent the workman who is utilizing the same. The manner in which uppers are placed upon the arms 1, 1, and piled up in stacks thereon, is represented in dotted lines in Fig. 1.

At 1^a, 1^a, are the reduced portions of the arms 1, 1, which are located adjacent the free upper extremities of the said arms, and at 2 is the shackle or retainer. At 3, 3, are 45 the holes through the said shackle or retainer, through which the upper extremities of the arms 1, 1, are adapted to be passed in applying the shackle or retainer to the arms or removing it therefrom, and at 4, 4, 50 are the slots extending transversely away from the said holes 3, 3, and designed to be occupied by the reduced portions 1^a, 1^a. The said slots 4, 4, are of a width less than the diameter of the holes 3, 3, but while 55 adapted to accommodate the reduced portions 1^a, 1^a, are too narrow to admit the large portions of the said arms above and below the said reduced portions. In this instance, the holes 3, 3, are formed close together 60 near the middle of the length of the shackle or retainer, and the slots 4, 4, extend outwardly from the respective holes toward the respective ends of the shackle or retainer. At 6 is a stem which is attached by 65 its lower end to the middle of the shackle

or retainer, between the two holes 3, 3, its upper portion being formed into a suspensory hook 6^a, by means of which the horse may be hung upon a convenient support, for instance, in storing the same with a load 70 of uppers thereon.

At 7 is the locking device, it being in this instance a disk which is formed with a central hole fitting somewhat loosely the lower part of the stem 6. The said locking device 7 is mounted upon the said stem above the shackle or retainer 2, and is movable to a limited extent vertically upon the said stem. At 8 is the stop with which as aforesaid the stem is provided to limit the 80 extent of the movement of the locking device upward away from the shackle or retainer. This stop is formed in the present instance by flattening the stem at opposite sides thereof, so that portions of metal 85 which are displaced by the said flattening, project at opposite sides of the stem as indicated in Figs. 1 and 4. This stop, as stated hereinbefore, is located at such a distance from the shackle or retainer that it prevents 90 the locking member from separating bodily from the shackle or retainer to an extent equal to the extent of projection of the end portions of the arms 1, 1, above the shackle or retainer.

After the application of the shackle or retainer to the arms 1, 1, by inserting such arms successively into holes 3, 3, the spring of the arms causes them to spread apart and to retain the separated relation shown in 10 Fig. 1 with their reduced portions at the outer ends of the slots 4, 4. The shoulders on the said arms below and above the shackle or retainer prevent movement of the latter either downward or upward along the arms. 10 Consequently displacement or disengagement cannot occur. The locking member intervenes between the two arms, and in consequence of being of a diameter somewhat greater than the distance between the two 11 holes 3, 3, it prevents the arms from being moved farther inward than in Figs. 2 and 3, and consequently neither arm can be moved from its slot into the corresponding hole until the locking member is especially 1 manipulated in a manner to permit. The stop 8 prevents the locking member from assuming a position in which both arms are unlocked simultaneously, either in case the said member is thrown accidentally against 1 the stop, or in case it is moved into contact therewith by hand. In order to effect the unlocking and removal of the shackle or retainer, it is necessary to move the locking member up to the stop and then tilt such member so as to clear the extremity of one arm 1, as in Fig. 5, which will permit such arm to be moved inward into the adjoining hole 3 and withdrawn therethrough, and then tilt the locking member in the reverse

direction in order that the other arm may be released and withdrawn.

As will be apparent, the application of the shackle or retainer to the arms 1, 1, is effected by an inverse series of operations, which will be understood from the foregoing.

What is claimed as the invention is,—

1. In a handling-horse, the combination 10 with opposite arms having reduced portions adjacent the free ends thereof, of a shackle having holes through which the extremities of said arms may be passed, and having also slots leading away from said holes and into 15 which the said reduced portions of the arms may enter by transverse movement from said holes, a stem, and a locking member movable along said stem and adapted to engage with said arms to lock them in the 20 slots, said stem having a stop for said locking member limiting the bodily movement of the same from the shackle to less than the extent of projection of the end-portions of the arms beyond the shackle, said locking 25 member adapted to be tilted relative to the stem to permit the arms to be pressed alternately along the slots into the holes to un-

lock the shackle and permit removal of the same.

2. In a handling-horse, in combination, 30 two arms extending side by side, having reduced portions near the ends thereof, a shackle having inwardly located holes through which said ends may be passed and outwardly extending slots in which the said 35 reduced portions of the arms may be retained, a stem rising from the intermediate portion of the said shackle, a locking washer movable upon said stem, and a stop limiting the extent to which the said washer 40 may be bodily separated from the shackle to less than the extent of the projection of the ends of the arms above the said shackle, said washer adapted to be tilted to enable an edge-portion of the same to clear one of the 45 said ends at a time, and the arms to be disengaged successively.

In testimony whereof I affix my signature in presence of two witnesses.

MARTIN A. HAYWARD.
